CLAIM

The ornamental design for a scanner, as shown and described.

DESCRIPTION

FIG. 1 is front view of the embodiment of a scanner.

FIG. 2 is a rear view of the embodiment of FIG. 1.

FIG. 3 is a left side view of the embodiment of FIG. 1.

FIG. 4 is a right side view of the embodiment of FIG. 1.

FIG. 5 is a plan view of the embodiment of FIG. 1.

FIG. 6 is a bottom view of the embodiment of FIG. 1.

FIG. 7 is a front, left, elevated perspective view of the embodiment of FIG. 1.

FIG. 8 is a front, right, lower perspective view of the embodiment of FIG. 1.

FIG. 9 is a rear, left, elevated perspective view of the embodiment of FIG. 1.

FIG. 10 is a rear, right, lower perspective view of the embodiment of FIG. 1.

FIG. 11 is a front, left, elevated perspective view of the embodiment of FIG. 1; and,

FIG. 12 is a rear, right, lower perspective view of the embodiment of FIG. 1.
